UNITED STATES PATENT OFFICE.

ANNA LOUISE JACKSON, OF PHILADELPHIA, PENNSYLVANIA.

DESIGN FOR A FRUIT-SHREDDER.

SPECIFICATION forming part of Design No. 27,130, dated June 1, 1897.

Application filed April 17, 1897. Serial No. 632,675. Term of patent 7 years.

To all whom it may concern:

Be it known that I, ANNA LOUISE JACKSON, a citizen of the United States, residing at Philadelphia, in the county of Philadelphia and 5 State of Pennsylvania, have invented and produced a new and original Design for Fruit-Shredders, of which the following is a specification, reference being had to the accompanying drawings, forming a part thereof.

- o In the drawings forming part of this specification, Figure 1 is a plan view showing my new design; Fig. 2, a transverse section on the line 2 2, and Fig. 3 a transverse section on the line 3 3 of Fig. 1.
- 5 As shown in the drawings, the leading or material feature of my design consists of a handle A, which is semicircular in cross-section and which is provided at one end with a semicircular head B, on which is formed a plurality of prongs or projections C, which are curved longitudinally and transversely into the form of a spoon, the head B being also similarly curved, and the end of the han-

dle A opposite the head B is pointed, as shown at D, and the groove formed in the handle of the spoon extends from one end thereof to the other. It will be seen that the handle of the shredder is concave on one side in cross-section and convex on the other, and the head B, with which the prongs C are connected, is 30 plain on its opposite side, but may be engraved, chased, or otherwise ornamented, as desired.

Having fully described my design, I claim as new and desire to secure by Letters Patent— 35

The design for a fruit-shredder herein shown and described.

In testimony that I claim the foregoing as my invention I have signed my name, in presence of the subscribing witnesses, this 10th 40 day of April, 1897.

ANNA LOUISE JACKSON.

Witnesses:

JOHN J. TURNER,
F. HOPPE.
